UNITED STATES PATENT OFFICE.

ERNEST CANTRELL, OF NASHVILLE, TENNESSEE, AND SIDNEY B. KAHNWEILER, OF NEW YORK, N. Y.

DESIGN FOR A KEY-HOOK.

46,019.

Specification for Design.

Patented June 30, 1914.

Application filed February 20, 1914. Serial No. 820,078. Term of patent 14 years.

To all whom it may concern:

Be it known that we, ERNEST CANTRELL, a citizen of the United States, and resident of Nashville, county of Davidson, and State of Tennessee, and SIDNEY B. KAHNWEILER, a citizen of the United States, and resident of the city, county, and State of New York, have invented a new, original, and ornamental Design for a Key-Hook, of which the following is a specification, reference being had to the accompanying drawings, forming part thereof.

view at the other side of our new design for key hook.

We claim—

The ornamental design for a key hook substantially as shown.

ERNEST CANTRELL.
SIDNEY B. KAHNWEILER.
